UNITED STATES PATENT OFFICE

138,227

DESIGN FOR A COFFEE STRAINING CONTAINER

Theodore P. Kouvallis, Chicago, Ill.

Application April 11, 1944, Serial No. 113,219

Term of patent 14 years

(Cl. D44—26)

To all whom it may concern:

Be it known that I, Theodore P. Kouvallis, formerly a subject of Greece, who have foresworn my allegiance to said country and declared my intention of becoming a citizen of the United States, and therefore am not now a citizen or subject of any country, residing at Chicago, in the county of Cook and State of Illinois, have invented a new, original, and ornamental Design for Coffee Straining Containers, of which the following is a specification, reference being had to the accompanying drawings, forming part thereof,

Fig. 1 is a front elevational view of a coffee straining container, showing my new design;

Fig. 2 is a top plan view;

Fig. 3 is a view from the left-hand side of Fig. 1, partly in section; and

Fig. 4 is a sectional view taken on the line 4—4 of Fig. 1 and in the direction of the arrows.

I claim:

The ornamental design for a coffee straining container, as shown,

THEODORE P. KOUVALLIS.
